DESIGN FOR A FLY SWATTER BLADE

Albert L. Murray, Auburn, Ind.

Application April 22, 1936, Serial No. 62,240

Term of patent 7 years

To all whom it may concern:

Be it known that I, Albert L. Murray, a citizen of the United States, residing at Auburn, in the county of De Kalb and State of Indiana, have invented a new, original, and ornamental Design for Fly Swatter Blades, of which the following is a specification, reference being had to the accompanying drawing, forming part thereof.

Figure 1 is a plan view of a fly swatter blade and Fig. 2 is an elevation of the same, showing my new design.

I claim:

The ornamental design for a fly swatter blade, as shown.

ALBERT L. MURRAY.
